UNITED STATES PATENT OFFICE.

GEORGE W. FERGUSON, OF SHEBOYGAN, WISCONSIN.

TARGET-BOARD.

1,023,634.

Specification of Letters Patent.

Patented Apr. 16, 1912.

Application filed July 7, 1911. Serial No. 637,258.

To all whom it may concern:

Be it known that I, GEORGE W. FERGUSON, a citizen of the United States, and a resident of Sheboygan, in the county of 5 Sheboygan and State of Wisconsin, have invented a new and Improved Target-Board, of which the following is a full, clear, and exact description.

My invention relates generally to toys and 10 more particularly it is directed to a target board of improved construction especially adapted for children.

The object of my invention is to provide a new and improved target which is made up 15 of a board having an opening therein, together with a number of independent parts suitably supported on one side of the board, the lowest part being exhibited adjacent the opening, removal of this part from view 20 permitting the next succeeding part to come into view and so on successively until all of the parts have been exposed.

A further object of my invention is to provide a new and improved toy of simple construction adapted to be used with a toy gun or, in fact, with any form of a projectile, the toy being of the nature of a target made up of a board having an opening therein, there being a number of successive pictures 25 adapted to be successively exposed adjacent the opening, any one of the pictures being adapted to be dislodged from view by a suitable missile, the next succeeding picture then coming into view.

30 A further object of my invention is to provide a new and improved target made up of a board having channels on the rear thereof, there being an opening in the board and positioned between the channels, the channels 35 being adapted to maintain in successive position a number of elements having pictures thereon, the element in exposed position being adapted to be dislodged from view by being struck with a missile whereby the next 40 succeeding element comes into view.

Other objects and advantages of the invention will appear as the description thereof proceeds, the new and useful features thereof being included within the appended 45 claims.

Reference is to be had to the accompanying drawings, forming a part of this specification, in which similar characters of reference denote corresponding parts in all the 50 views, and in which—

Figure 1 is a front view of the target

board; Fig. 2 is a rear view thereof; Fig. 3 is a vertical sectional view thereof; Fig. 4 is a partial rear view showing a slightly modified form of construction.

The board comprises any suitable stationary member 1 on which any scene is painted, preferably a forest or a jungle scene, the board being maintained in upright position by engagement with any suitable form of supporting members 2, 3. At a suitable point of the picture set forth on the board a portion of the board is removed and an opening is formed along the lines *a*, *b*, *c*, *d*, of Fig. 1, the back of the board being provided with means for holding in exposed position behind this opening any one of a number of successive parts, each of which has thereon the picture of an animal, the scene surrounding the animal being suited 60 to the scene set forth on the board proper.

A pair of uprights 4, 5, is suitably arranged on the back of the board and at a suitable distance therefrom by any suitable means such as a spacer block 6, 7, whereby 65 channels may be formed, the channels being adapted to receive successively the parts 8, 9, 10, 11. Each of these parts is entire in itself and each is adapted to occupy successively the position occupied by the part 8, 70 as is shown in Fig. 2, whereby the picture thereon is exposed within the opening in the board proper previously mentioned. In order to provide for holding these parts in 75 position and at the same time permitting the lower one to be dislodged from such position when struck by a ball, or, in fact, any article thrown at it, the uprights 4, 5, adjacent their lower ends and for a distance a little less than the height of any one of the 80 parts 8, 9, 10, 11, are cut away so that a blow on the front of the part 8 in this instance will throw it backwardly and out of engagement with the target, the part 9 then dropping into view. The part 8 rests on a suitable 85 transverse support 12 carried by the board so that while it is supported in position it may be easily knocked therefrom, as indicated by the arrow in Fig. 3. In Fig. 4 I have shown a slightly modified form of 90 construction in that one of the uprights 4 adjacent this lower end is removed for a distance a little greater than the height of the part 8, this part, however, being removable 95 secured in exposed position by means of the channel between the upright 4 and the rear of the target board.

100

105

110

The board may be of any suitable dimensions and the parts 8, 9, 10, 11, may be positioned thereon in any desired sequence or the number of these parts may be as desired, 5 the idea being that when the part 8 is exposed, as shown in Figs. 1 and 2 particularly, the part may be thrown backwardly and out of view by being struck by some suitable article, the part 9 then dropping 10 into view, which in its turn may be dislodged from view when the other parts 10, 11, etc., follow on successively. The board is especially adapted for use as a toy although it is obvious that it may be made of considerable 15 size and set up as a target, the shape and size of the opening within the board being capable of wide variation and the pictures thereon being also largely a matter of choice, the particular scene on the board or 20 the particular number of parts successively displayed being as occasion may require.

Having thus described my invention, I claim as new, and desire to secure by Letters Patent:—

25 1. A target comprising a board having an opening therein, a plurality of independent parts suitably supported by one side of the board in successive position, one of the parts being adjacent the said opening, dislodgment of the said part from the opening permitting the next succeeding part to move adjacent the said opening.

30 2. A device of the class described comprising a board having an opening therein, a plurality of separate parts removably carried by the back of the board, each of the said parts bearing a suitable picture, the lowest part being in the rear of the said opening whereby the picture thereon may be 35 seen through the opening, the said lowest part being capable of dislodgment and removal from view, the next succeeding part then coming into view.

35 3. A device of the class described comprising a board having an opening therein, the board containing any suitable scene, a plurality of parts independently and slidably positioned on the back of the board, each of the said parts containing a picture 40 suited to the picture on the board, the lowest one of the said parts being in the rear of the said opening whereby the picture thereon may be seen, the said part being adapted to be dislodged and removed from view, 45 the next succeeding part then coming into view.

40 4. A device of the class described comprising a board having an opening therein, a plurality of channels on the rear of the 50 board, a plurality of separate parts slidably positioned within the channel, the lowest one of the said parts being positioned in the rear of the said opening whereby any picture on the said part may be seen through 55 the opening, the channels being so con-

structed adjacent their lower portion that the said lowest part may be dislodged therefrom and removed from view, thereby permitting the next succeeding part to come into view.

5. A device of the class described comprising a board having an opening therein, a plurality of channels on the rear of the board, a plurality of parts slidably positioned within the channels, the front of the 70 board containing any suitable scene, each of the said parts containing a picture suited to the scene, means for supporting the lowest part in position behind the said opening whereby the picture on the said part 75 may be seen through the opening, the said channels being removed adjacent the said lowest part whereby it may be removed from view and dislodged, the next succeeding part then coming into view.

85 6. A device of the class described comprising a board having an opening therein, a plurality of uprights on the rear of the board whereby channels are formed, a plurality of parts slidably positioned within the channel, each of the parts containing a picture, the front of the board containing a suitable scene, together with means for supporting the lowest of the said parts in position adjacent the said opening whereby 90 the picture on that part may be seen through the opening, portions of the said uprights being removed adjacent their lower ends and adjacent the said lowest part whereby 95 that part may be dislodged by being struck on its front side, thereby moving it out of view and permitting the next succeeding part to come into view.

100 7. A device of the class described comprising a board having an opening therein, a suitable picture being carried by one side of the board, a number of independent parts adjacent the opposite side of the board, the said parts being arranged one after the other and each of the parts being provided 105 at one side with a picture adapted to be exposed through the opening in the board, together with means for slidably supporting the said parts in position, the construction and arrangement being such that the lowest 110 one of the said parts may be thrown back of the board and out of exposed position, thereby permitting the next succeeding part 115 to come into view.

120 8. A device of the class described comprising a board having an opening therein, one side of the board being provided with a suitable scene, a part on the opposite side of the board, one side of the said part being provided with a picture adapted to be seen 125 through the opening in the board, together with means for holding the said part in position, the said part being adapted to be thrown back of the board by being struck.

130 9. A device of the class described com-

prising a board having an opening therein, a scene on one side of the board, a number of independent parts carried on the opposite side of the board, together with means for holding each part successively exposed adjacent the opening, and other means for holding the said parts in position before they come into exposed position.

10. A device of the class described comprising a board having an opening therein, the front of the board bearing a suitable scene, uprights carried on the back of the board and suitably spaced therefrom in order to form channels, a support extending transversely of the board and adjacent the lower ends of the said uprights, each of the said channels terminating at a suitable distance above the said support, together with a number of parts positioned one above the

other in the said channels, one side of each of the parts bearing a picture, each part being adapted to be successively positioned adjacent the opening in the board whereby the picture on the part can be seen on the front of the board and through the opening, the part exposed being adapted to be dislodged by a suitable missile whereby the next succeeding part comes adjacent the opening and the picture thereon is seen through the opening.

In testimony whereof I have signed my name to this specification in the presence of two subscribing witnesses.

GEORGE W. FERGUSON.
